UNITED STATES PATENT OFFICE.

HARRY GOLDSMITH AND SAMUEL WERNER, OF CHICAGO, ILLINOIS.

STROPPER FOR RAZOR-BLADES.

No. 926,865.

Specification of Letters Patent.

Patented July 6, 1909.

Application filed October 9, 1908. Serial No. 456,971.

To all whom it may concern:

Be it known that we, HARRY GOLDSMITH and SAMUEL WERNER, citizens of the United States, residing at Chicago, in the county of 5 Cook and State of Illinois, have invented certain new and useful Improvements in Stroppers for Razor-Blades, of which the following is a specification.

This invention relates to improvements in 10 a device or appliance to be used for stropping razor-blades and other instruments which require very sharp edges, and while it is more especially intended for holding and stropping blades of safety-razors of various 15 makes, yet it is, with slight changes, applicable for use in stropping or sharpening the blades of ordinary razors, or other kinds of blades; and it consists in certain peculiarities of the construction, novel arrangement, 20 and operation of the various parts thereof, as will be hereinafter more fully set forth and specifically claimed.

The principal object of the invention is to 25 provide a strop for razor-blades and the like which shall be simple and inexpensive in construction, strong, durable and efficient in operation, and so made that the stropping or sharpening operation may be successfully and properly performed by an 30 unskilled person and without injury to the blade or danger of cutting the hands of the operator.

Another object of the invention is to 35 provide a simple and efficient holder for the blades, to be used in connection with the rotary strop, and which forms a part of the invention.

Other objects and advantages of the 40 invention will be disclosed in the subjoined description and explanation.

In order to enable others skilled in the art 45 to which our invention pertains, to make and use the same, we will now proceed to describe it, referring to the accompanying drawing, in which—

Figure 1 is a central vertical sectional view through the rotary strop and frame therefor, showing a razor-blade held in stropping position thereon by means of a 50 blade-holder embodying one of the forms of said holders; Fig. 2 is a fragmental view in elevation of the upper portion of one side of the supporting-frame for the rotary strop, showing by dotted lines the normal position 55 thereon of one of the blade-holders; Fig. 3 is a plan view of a blade-holder embodying

one form of the invention therein; Fig. 4 is a similar view of a blade-holder, showing a modification in the construction thereof; Fig. 5 is a cross-sectional view thereof taken on line 5—5 of Fig. 4 looking in the direction indicated by the arrows; Fig. 6 is a plan view of still another modified form of the blade-holder; and Fig. 7 is a cross-sectional view thereof taken on line 7—7 of Fig. 6 looking in the direction indicated by the arrows.

Like numerals of reference, refer to corresponding parts throughout the different views of the drawing.

The reference numeral 10 designates a cylindrical roller which may be made of any suitable size and material, but usually of wood, and has its periphery covered or provided with suitable stropping material 11, 75 such as leather. The roller or rotary strop 10 is centrally mounted on a shaft 12 which is horizontally journaled at its ends in uprights 13 located at each end of a base 14 which uprights and base constitute the supporting-frame for the rotary part of the strop. One end of the shaft 12 is provided with a crank-handle 15 by means of which the roller 10 may be turned. The upper end of each of the uprights 13 of the supporting-frame is provided with a horizontally disposed recess 16 which extends from one of the edges thereof inwardly and has its floor or bottom rounded or downwardly and inwardly curved at its inner portion as is 90 clearly shown at 17 in Figs. 1 and 2 of the drawing. Secured to the upper end of each of the uprights 13 is a spring 18 which are extended over the rounded or cutaway portion 17, and together with said parts produce the recesses 16 which are for the reception and operation of lateral and flat extensions 19 with which the blade-holder is provided at each of its ends.

Referring now to Figs. 1 and 3 of the drawing, the blade-holder consists of a flat body portion 20 which is preferably rectangular in shape and of any suitable size and material, and has at each of its ends a flat extension 19 to fit and operate in the recesses 16 of the supporting-frame, as before stated. The body 20 is provided on one of its surfaces near one of its edges with two spaced apart pins 21 to fit in correspondingly spaced openings 22 in the razor-blade 23 which is shown 110 in Figs. 1 and 3 of the drawing as being of that type known as the "Gillette" blade.

2
Located on the opposite edge of the body 20 is a clamp 24 which is provided at about the middle of its outer portion with an extension 25 to be used in tilting the holder to the 5 position shown in Fig. 1 during the operation of stropping the blade. This clamp preferably has its free edges outturned as at 10 26 to cause it to readily pass over the inner edge of the blade 23, and its members are sufficiently separated to permit of the reception of the body 20 and a portion of the 15 blade 23, yet so as to hold the two firmly together.

In Figs. 4 and 5 is shown a modification 20 in the construction of the holder which consists in forming the body portion 20^a thereof with lateral extensions 19 at its ends and with a tilting extension 25 at about the middle of one of its edges. The lower portion 25 of each end of the body 20^a in the modification now under consideration is provided with an inturned flange 27 which have their edges spaced a slight distance from the upper surface of the body 20^a and are inclined 30 toward each other at their lower ends as is clearly shown in Fig. 4 of the drawing, so that the blade may be inserted downwardly between the two flanges and body where it will be securely held with its lower edge extended far enough below the lower edge of 35 the body 20^a to contact with the stropping material 11 on the roller when tilted for the stropping operation.

In Figs. 6 and 7 is shown another modification 40 in the construction of the blade-holder which consists in forming the tilting extension 25 and lateral extensions 19 of a single piece, and placing thereon a clamp 24^a which is provided with a central opening 28 at the middle of its upper edge through 45 which the extension 25 is passed. In this latter construction the parallel members 29 of the clamp 24^a are spaced apart sufficiently to permit of the insertion therebetween of the razor-blade which will be held in such position by means of the clamping action of the members 29 of said clamp.

From the foregoing and by reference to the drawing it will be clearly seen and readily understood that by placing the extensions 19 of 50 any one of the blade-holders above-described within the recesses 16 between the springs 18 and the top of the cutaway parts of the uprights 13 the holder will be retained by the 55 action of said springs in substantially a horizontal position, as shown by dotted lines in Fig. 2, and so that the blade carried by the holder will be out of contact with the stropping material 11 on the rotary cylinder or 60 roller. When it is desired to strop or sharpen the blade the holder may be tilted by means of one hand of the operator to the position shown in Fig. 1 while the rotary stropper may be turned with the other hand applied

to the crank-handle 15 on one end of the 65 shaft of the roller. As the extensions 19 are flat, it is apparent that they will rock on the rounded portion 17 of the uprights so that their lower edges will extend into the downwardly and inwardly inclined portions of the 70 recesses 16 while their upper edges will rest against the lower surfaces of the springs 18 as long as tilting pressure is applied to the holder, which may be done by applying the hand to the tilting extension 25 and blade-clamp or the body of the holder. As soon as the hand is removed from the holder, it is apparent that the springs 18 will press the upper edges of the extensions 19 downwardly, and thus remove the blade from the rotary 80 stropper.

If it is desired to use the holder shown in Figs. 1 and 3 of the drawing for other blades than that of the "Gillette" type or without holes, it is apparent that the holder may be 85 turned over from the position shown in Fig. 1 and the blade placed on the surface thereof opposite that having the pins thereon where it will be held by means of the clamp.

Having thus fully described our invention, 90 what we claim as new, and desire to secure by Letters-Patent, is—

1. The combination with two spaced apart uprights, of a stropping roller journaled therebetween, a spring secured on the upper 95 end of each of said uprights and extended slightly above a portion of the upper end of each of the same, and a blade-holder having at each of its ends an extension adapted to be inserted between the said springs and upper 100 parts of said uprights.

2. The combination with two spaced apart uprights, of a stropping roller journaled therebetween, means to turn the roller, a spring secured on the upper end of each of 105 said uprights and extended slightly above a portion of the upper end of each of the same, a blade-holder consisting of a body portion having at each of its ends an extension adapted to be inserted between the said springs 110 and upper parts of said uprights, and means on the body portion of the holder to hold a blade in position thereon.

3. The combination with two spaced apart uprights having their upper ends formed 115 with an inwardly and downwardly inclined cutaway part, a spring secured on the upper end of each of said uprights and extended over said cutaway portions, and a blade-holder having at each of its ends an extension 120 adapted to be inserted between said springs and the upper surfaces of the cutaway part of the uprights.
